UNITED STATES PATENT OFFICE.

JOHN BOWERS RHODES, OF MEMPHIS, TENNESSEE.

GANG-PLANK.

SPECIFICATION forming part of Letters Patent No. 531,860, dated January 1, 1895.
Application filed December 11, 1893. Serial No. 493,431. (No model.)

To all whom it may concern:

Be it known that I, JOHN BOWERS RHODES, a citizen of the United States, residing at Memphis, in the county of Shelby and State of Tennessee, have invented certain new and useful Improvements in Gang-Planks; and I do hereby declare the following to be a full, clear, and exact description of the invention, such as will enable others skilled in the art to 5 which it appertains to make and use the same.

This invention relates to an improvement in gang planks for transferring merchandise from the deck of a vessel to the wharf or shore-bank, or vice versa, and the object in view is to provide simple, strong and durable mechanism by which the transfer of merchandise can be quickly and easily effected without requiring laborers or trucks to carry the freight, &c., over the gang plank from the 10 vessel to the wharf or bank.

In loading or unloading a steamer or vessel at wharves it is not unfrequently the case that the gang plank is pitched at such an angle that it is difficult for the deck hands or laborers to expeditiously transport the freight to or from the deck, and it sometimes occurs, where the bank or wharf is considerably above the level of the deck, that the deck-hand slips and falls and the freight is precipitated into 15 the water. I overcome this objection by providing an improved gang plank on which the freight can be placed and carried to the wharf or deck according as it is desired to transport the freight from either the shore or deck; and to the accomplishment of these ends, the first 20 of my invention consists in the combination with a supporting frame comprising longitudinal side pieces or gunnels, of a fixed track supported within said frame and extending 25 longitudinally thereof, and a traveling conveyer provided with rollers adapted to travel 30 on said longitudinal fixed track and supported by suitable transverse shafts at the ends of the supporting frame, one of which 35 shafts serve as the means for propelling the 40 conveyer.

My invention further consists in the combination with a suitable supporting frame such as herein referred to, of a conveyer of 45 novel construction. In the preferred embodiment of my conveyer for gang planks, I

provide two endless chains which are arranged side by side at a suitable distance from each other, and each conveyer consists of links which are forked or bifurcated at one end to 55 embrace the tail of the preceding link and has its other end recessed to accommodate a friction roller; and through the meeting ends of two adjacent links and the friction roller is passed a pin which serves to pivotally connect the links and the shaft on which the friction roller is mounted so as to be free to rotate when it rides upon the track within the supporting frame. Each link of the chains is provided with a socket on its inner face to 60 accommodate a tooth on the sprocket of the driving or idler wheels; and the corresponding links of the two chains are fastened to a transverse slat in any suitable way. Each slat is thus fastened to corresponding links 65 of the adjacent endless chains, and thus the conveyer is practically made of endless chains which carry a large number of slats which are exposed and forming practically a continuous surface on which the freight can be 70 placed and at the same time this slatted surface has the necessary flexion motion to pass around the driving and idler sprocket wheels at the ends of the supporting frame, the conveyer thus constructed being prevented from 75 sagging under the weight of its load by the friction rollers riding upon the longitudinal fixed track beneath the upper side of the conveyer.

My invention further consists in the peculiar construction of parts and combination of devices as will be hereinafter more fully described and pointed out in the claims.

I have illustrated the preferred embodiment of my invention in the accompanying 80 drawings, forming a part of this specification, in which—

Figure 1 is a plan view of my improved gang plank. Fig. 2 is a view partly in side elevation and partly broken away to show the 85 interior construction of the gang plank at one end thereof. Fig. 3 is a view partly in section and partly in elevation showing one of the track rails, the friction rollers bearing thereon, two of the chain-links and the slats connected to said links. Fig. 4 is an enlarged detail view, in bottom plan, of a series of links 90 100

and their friction rollers, to more clearly show the construction of the links, the manner of connecting them together, and supports for the friction rollers.

- 5 Referring to the drawings, in which like letters of reference indicate corresponding parts in all the figures, A denotes the supporting frame of my improved gang plank, and B is the endless conveyer which is arranged within 10 said frame and supported thereby in operative position. This frame, A, comprises two outside gunnels or side pieces, c, c, and a series of transverse pieces or bars, d, d, which extend across the frame and are rigidly fastened to 15 the side pieces to present a substantial durable structure. The transverse pieces or bars, d, are of less width than the gunnels and they are secured centrally thereto so as to lie within the edges of said gunnels, as indicated in Fig. 2. 20 To the upper sides of these transverse bars, d, are secured the stringers, D, D, which extend longitudinally of the frame A, parallel with the gunnels, c, and which stringers form the track on which the friction rollers of the endless conveyer are designed to ride or bear to 25 prevent the conveyer from sagging under the load on the slats thereof. At one end of the supporting frame and the track, is arranged a transverse shaft, E, which is suitably journaled in the frame; and on this shaft is provided the sprocket wheels, e, with which engage the chains of the conveyer. One end of this shaft is extended beyond one of the gunnels, c, and on this protruding end of the 30 shaft is secured a gear pinion, f, which is designed to mesh with a driving pinion, indicated at g, in Fig. 1, which driving pinion is carried by a shaft which has connections with an engine on the steamer for the purpose of 35 imparting positive movement to the endless conveyer.

The endless conveyer consists of the chains, E', F, and the transverse slats, G, which are secured to the adjacent links of the chains. 40 Each chain is made up of a series of links, g', of the form shown by Figs. 3 and 4 of the drawings, and the wide end of each link is forked or bifurcated to provide the lugs, g'', while the other, narrow end of the link is formed 45 with a central recess, h. A friction roller, H, is fitted in the recess, h, of each link, and the forked end of one link is fitted around the narrow end of the adjoining link. The links are pivoted by means of the transverse pin, I, 50 which is passed through the lugs g' of one link and the narrow recessed end of the adjacent link, and said pin also passes through the friction roller, H, and serves as the support therefor, said roller being free to revolve on the pin 55 or shaft. Each link is further provided with a socket, J, which is made in the solid central part thereof between the forked wide end and the narrow recessed end, and this socket receives the tooth on the sprocket wheels located at the ends of the supporting frame.

The slats, G, extend across from one chain to the other, and they are fastened to said

chains by means of the transverse screws or bolts, j, which pass through the slats and into a threaded socket in the solid part of the link. The slats are fastened to the links at the middle thereof, and they are of such width that the side edges thereof overhang the adjacent rollers, as indicated in Fig. 4, the lower inner edges of the slats being recessed 70 as at k to adapt the rollers to fit snugly and make a compact construction. 75

At the end of the frame A opposite to the driving shaft E is journaled an idler shaft, L, which is provided with sprocket wheels, l, and 80 forming the support for the far end of the conveyer.

This being the construction of my gang plank, the operation may be briefly described as follows:—The end of the gang plank having the idler shaft and wheels is shoved out from the deck to rest on the wharf or bank while the other end of the gang plank rests upon the deck in such position to the driving gear and its shaft that the wheel f thereof 90 meshes with the driving gear. The conveyer is thus propelled by the driving gear, and the freight or merchandise is placed on one end of the conveyer and carried to the other end without the intervention of manual labor, 95 whereby the steamer can be loaded and unloaded with dispatch.

In practice I prefer to make the gunnels or side pieces c of the supporting frame of such width that the lower side of the conveyer will 100 not contact with the wharf or the deck.

Having thus fully described my invention, what I claim as new, and desire to secure by Letters Patent, is—

1. A gang plank, substantially such as described, comprising a suitable frame, longitudinal track-stringers fixed within the sides of said frame, driving and idler shafts journaled in the respective ends of the frame and provided with sprocket wheels, the endless 110 chains passing around the sprocket wheels of said shafts and having each of the pivoted links constructed with a recess or socket between the wide and narrow end thereof to receive teeth on the sprocket wheels and each 115 link provided with a friction roller, within its narrow end, which rides upon one of said longitudinal stringers, and transverse slats fastened to the middle of corresponding links in the endless chains and said slats having 120 their edges overhanging the friction rollers, as and for the purposes described.

2. In a gang plank, substantially such as described, the endless chains consisting of pivoted links, each link of which is cast in a 125 single piece with a wide forked end, a narrow slotted end, and a tooth-receiving socket in the solid middle portion between said ends, the shafts or pins each of which passes through the narrow slotted end of one link 130 and the wide forked end of an adjoining link, and a friction roller fitted on each shaft or pin and within the narrow slotted end of the link, in combination with a frame, track-

stringers fixed within the sides of the frame for the friction rollers of the chains to ride thereon, driving and idler shafts journaled in the frame beyond the stringers and having 5 sprocket wheels which have their teeth fitted in the sockets of the links, and slats fastened to the links of the chains, as and for the purposes described.

3. In a gang plank, substantially such as 10 described, the endless chains consisting of links each of which is made in a single piece with a slot at one end, forked arms at its other end, a tooth receiving socket in the inner face of its solid middle portion, and 15 with a threaded aperture for a slat-fastening screw, the pins which pivot the lapped ends of said links together, and friction rollers

journaled on said pins within the slotted ends of the links, combined with a frame, longitudinal track-stringers therein for the friction rollers to ride upon, driving and idler shafts provided with sprocket wheels which engage the socketed middle parts of the chain-links, and slats fastened to the chain links by screws that work in the threaded 20 apertures of said links and said slats having their edges recessed to overhang the friction rollers, as and for the purposes described.

In testimony whereof I affix my signature in presence of two witnesses.

JOHN BOWERS RHODES.
